UNITED STATES PATENT OFFICE.

ANDREW L. RIKER, OF BRIDGEPORT, CONNECTICUT, ASSIGNOR TO THE "LOCOMOBILE" COMPANY OF AMERICA, OF NEW YORK, N. Y., A CORPORATION OF WEST VIRGINIA.

INTERNAL-COMBUSTION ENGINE.

1,181,252.

Specification of Letters Patent.

Patented May 2, 1916.

Application filed May 29, 1905. Serial No. 262,758.

To all whom it may concern:

Be it known that I, ANDREW L. RIKER, a citizen of the United States, residing at Bridgeport, in the county of Fairfield and State of Connecticut, have invented an Improvement in Internal-Combustion Engines, of which the following description, in connection with the accompanying drawings, is a specification, like letters on the drawings representing like parts.

My invention consists in improvements in internal combustion engines, being particularly concerned with means for controlling the operation thereof.

My invention will be best understood by reference to the following description when taken in connection with the accompanying drawings showing for illustrative purposes one specific embodiment thereof, while its scope will be more particularly pointed out in the appended claims.

In the drawings.—Figure 1 is a side elevation of an automobile engine embodying one form of my invention; Fig. 2 is a sectional view of the same taken on the line 2—2, in Fig. 1; Fig. 3 is a side elevation of a portion of the cam shaft, the remainder being broken away; Fig. 4 is a section on the line 4—4, in Fig. 3 and Fig. 5 is a detail of the controlling lever.

In the drawings I have shown in Fig. 1 a four-cylinder automobile internal combustion engine. Each cylinder is provided with an appropriate sparking or ignition timing device *a*, herein a "make and break" sparking device, actuation of which is effected by a vertically reciprocated cam rod *b*, which passes through the crankshaft casing *C* and carries at its lower end the cam roller *c* engaging with the igniter cam *d* which is preferably formed integrally with and upon the cam shaft *e*. The latter extends lengthwise the engine frame and is rotated from the main crankshaft as by suitable gearing indicated at one end. Each cylinder is also provided with an appropriate admission valve *e'* (Fig. 2) and exhaust valve *f*. The former is raised and lowered for admission and cut-off of the fuel at the proper times by the vertically reciprocating valve rod *g* carrying the cam roller *h* engaging with a cam *i* also formed upon the cam shaft *e*. The exhaust valve *f* is actuated by the valve rod *j* (Fig. 2) cam roller *k* and cam *l* on the exhaust cam shaft *m*, the latter being arranged lengthwise the engine on the opposite side thereof from the cam shaft *e* but also within the casing *C*. The cam shaft *e* therefore has four ignition cams and four admission cams and the cam shaft *m* has four exhaust cams, one for each cylinder, the same being arranged so that the several events, namely,—admission, exhaust and ignition, occur in each cylinder at the appropriate times.

Where an internal combustion engine is operated at a variable speed as where used to propel an automobile it is necessary to vary the time of ignition relative to the other events of the engine stroke to correspond with the required variations in speed. When an increased speed is required the time of ignition is ordinarily advanced to occur earlier in the engine stroke, while if a slower speed is sought the time of ignition is retarded. In order to permit this regulation of the ignition simultaneously for all the cylinders of the engine in a simple and effective way and without variation of the time of admission, I elongate the ignition and admission cams giving the effective face or edge *n* of each ignition cam a spiral form so as to have a constantly advancing relation lengthwise the cam shaft and make the entire cam shaft slidable lengthwise in its bearings. Sliding movement of the cam shaft *e* is controlled by the yoke *o* which may be moved by the lever *p* located outside the engine casing and attached to the rod *q*, the latter in turn secured to the rocking arm *r*. The arm *r* is secured to the vertical shaft *s*, the latter having at its bottom the beveled gear *t*, meshing with the gear *n*, the latter in turn being attached to the central rod *v* within the steering post *w*, which forms a part of the steering apparatus of the automobile upon which the engine herein described is supposed to be mounted. The steering post *w* carries at its head the steering wheel *w'*, to which is stationarily secured the notched segment *x*. The teeth of the segment are engaged by and act to hold in position the pin *y* secured to the spring lever *z*, the latter being attached to the end of the central rod *v*. Thus during the operation of the vehicle the operator whenever so disposed and desiring to advance or retard the ignition can withdraw the pin *y* from the toothed segment and shift the spring lever *z* to any new position desired.

along the segment, the movement of the lever resulting in the partial rotation of the central rod *v* and the consequent shifting of the cam shaft in its bearings. This results in an advancement or retardation of the time of ignition according as the cam shaft is shifted to the right or the left as viewed in Fig. 1, for the spiral edge *n* of the cam will meet the cam roller at an earlier or later period in the rotation of the cam shaft, according to the position lengthwise the cam at which the roller engages the same.

Details of the cam shaft as I have here constructed it are shown more particularly in Figs. 3 and 4. The ignition and admission cams having elongated faces are formed preferably in a single piece with the cam shaft *c*. The effective edge *n* of each ignition cam is spiraled to give the required timing change of the ignition on shifting of the shaft while the elements of the admission cam are parallel to the axis of the cam shaft in order to produce no timing change in the admission when the shaft is shifted. By the construction described the ignition cam shaft and the admission cam shaft are consolidated into a single shaft and this together with the cams and cam rollers as well as the exhaust cam shaft are contained within the oil tight engine casing *C* and may therefore be run in the oil which it is customary to place within such casing.

While I have herein shown one specific embodiment of my invention for purpose of illustrating the same, it is to be understood that it is in no wise limited to the specific details or the particular application thereof herein disclosed, but that many modifications and wide departure from the details described may be permitted without departing from the spirit thereof.

Claims:

1. The combination in an automobile of an internal combustion engine having an oil tight casing, an ignition cam shaft mounted for longitudinal movement within said casing, a member engaging said cam shaft and extending outside of said casing, a steering post, an operating rod passing through said steering post and provided at its lower end with a bevel gear, a shaft connected to said member, and a bevel gear meshing with said first mentioned bevel gear, whereby the turning of said steering post rod moves said cam shaft and varies the timing of the ignition.

2. In an automobile, the combination of an internal combustion engine having fuel supply means, ignition means an oil tight casing having a cam shaft mounted for longitudinal and rotative movement therein and provided with ignition means intermediate said cams and said fuel and ignition means for operating the same upon rotation of said shaft, and admission cams of an actuator having engagement with said shaft and extending outside said casing, a steering post, and means connected therewith for operating said actuator to slide said cam shaft for varying or controlling the timing of the ignition, but without affecting variation in admission, said ignition cams having spiral elements and said admission cams parallel elements for that purpose.

In testimony whereof, I have signed my name to this specification, in the presence of two subscribing witnesses.

ANDREW L. RIKER.
